WINDOW SCREEN

Filed April 7, 1930

Inventor:
RAYMOND L. GOOCH.
By *Henry L. Chenev.*
Attorney.

UNITED STATES PATENT OFFICE

RAYMOND L. GOOCH, OF FALMOUTH, MAINE, ASSIGNOR OF ONE-HALF TO STANLEY J. MAYHEW, OF SOUTH PORTLAND, MAINE

WINDOW SCREEN

Application filed April 7, 1930. Serial No. 442,234.

The invention to be hereinafter described relates generally to that well known device—a window screen. In the present instance this screen, due to its embodying certain novel features in its structure, is particularly well adapted for use in the windows of motor vehicles, and, although its primary object is in line with that of the ordinary house window screen, that is, to provide protection against flies, mosquitoes or other insect pests, it is susceptible of serving in other capacities which will be more fully dealt with as the description of the device proceeds.

Among the more specific objects and advantages of the invention, speaking in terms of structure, are:

1. The wedge shape rails, or marginal portions on three sides of the screen, insuring tight fitting joints between the screen and the window frame, regardless of the width of the groove in which slides the window pane.
2. A bottom rail which encompasses the top of the window pane and allows the latter, when raised, to force the whole screen upwardly and bring the top rail to a close fit within the upper groove in the window frame.
3. An automatic locking device which holds the two sections of the screen extended into the side grooves of the vehicle window frame.
4. The locating of this automatic locking device so that it operates on the inside of the vehicle only; largely doing away with petty thievery of articles left in the vehicle when parked on the street or highway, and
5. The small space required to store the screen when not in use—one portion telescoping the other and reducing its normal length by nearly one-half.

The character of the invention may best be understood by reference to the description found in the specification following when taken in connection with the accompanying drawing in which is disclosed one embodiment which, at the present time I consider preferable to other possible forms in which the invention might be carried out.

In the drawings—

- Fig. 1 is a side elevation of my screen;
Fig. 2 is the same, showing the screen

mounted in the window frame of a motor vehicle door;

Fig. 3 is a sectional elevation taken on line 3—3, Fig. 2;

Fig. 4 is a sectional plan taken on line 4—4, 55 Fig 2;

Fig. 5 is a fragmentary perspective view, partly in section, showing portions of the two sections of the screen including the locking device which holds the parts extended;

Fig. 6 is a view showing a detail of the junction of the side and bottom rails;

Fig. 7 shows a screen, in fragmentary form, mounted over a window pane of arcuate shape on its upper edge, and

Fig. 8 is a section taken on line 8—8, Fig. 7.

Similar reference characters are employed to identify like parts in all views of the drawing.

In Fig. 1 is shown a full side view of my 70 vehicle window screen. It comprises two sections, A and B, the top and bottom rails of one section telescoping those of the other.

The method of attaching the screen cloth 10a and 10b to the frame work of the respective sections, A and B is, in the present invention, not of material importance—any approved way may be adopted, but as shown it consists in partly shearing a plurality of tongues T through the inwardly disposed flanges of the rails and subsequently forcing these tongues into the depression made by the shearing, firmly engaging the screen cloth interposed between the tongue and flange. This is clearly shown in Figs. 5 and 6.

In Fig. 3 is shown a transverse section, vertically of the screen, illustrating the cross-sectional shape of the rails composing the frame work of the screen, the latter being disposed within the window space of an automobile door D, the frame 11 of which is provided with a groove in which slides the window pane P.

The rail 12a of the outer screen section A is made wedge shape—both sides flaring inwardly to form an apex which enters the window pane groove. Thus when the rail is forced upwardly into the groove 13 it centralizes therein and bears strongly on both corners of the groove effecting a close joint

between the screen and window frame, and this regardless of slight variations in the width of the groove.

The rail 12b of the telescoping section B snugly fits the inside of the rail 12a and its flaring edges also bear, for a greater portion of its length, on the corners of the groove 13—there being, in any event, a space near the overlapping point of the two rails insufficient to permit of the smallest fly or mosquito to enter or pass through.

The side rails 14a and 14b, being of the same type as the rails 12a and 12b the same conditions obtain with respect to the tightness of the joint made in the side grooves 15 when the sections A and B, respectively, are extended.

The bottom rails of the two sections are differently constructed. In Fig. 6 is shown the lower, left-hand corner of section A and it will be observed that the rail 16a forms an integral part of the vertical, side rail 14a and, preferably, is slightly concaved so as better to receive the upper edge of the window pane when raised to engage the screen. The cross-sectional shape of the rails 16a and 16b, however, is really immaterial so long as a proper joint is provided between the rails and the window pane.

In Fig. 7 is shown a condition in which it is essential that the bottom rails, 16a and 16b, be made with overhanging sides so as to encompass the arcuate-top window pane for its entire length. The cross-sectional view in Fig. 8 discloses the preferred form in this particular instance, and so as to permit of the rails telescoping, they are made straight—as depicted in Fig. 7.

One meritorious feature of my screen is the automatic or self-locking mechanism, illustrated in Figs. 1 and 5. Extending outwardly from the inner upright, 17b, of the section B, is a channel portion 18, pivoted on which is a pawl 19. On the rail 16a is an upwardly extending flange 20 provided on its top edge with a rack 21. When the two sections are extended or moved outwardly, the pawl engages the teeth of the rack in successive order until the rails 14a and 14b are firmly seated in the grooves 15. The two sections can now be retracted or brought together only after lifting the pawl out of the rack. A spring 22 tends to keep the pawl engaged, and the arm 19' serves as means by which to lift it.

In attaching accessories to any portion or part of an automobile one of the most essential precautionary measures which should be taken is to provide in so far as is possible against loosening of connections or rattle of the parts—this trouble of noise being highly objectionable to most individuals.

The principle involved in the method by which I obtain a vibration-proof installation of my screen on a moving body—as a motor

vehicle, can be carried out, I believe, in no other way so simple as the wedge-shape form of the top and side rails, except, of course, resort be had to bolts or other clamping means, which in this class of device would be hardly feasible.

The rails are self-centering in the window pane grooves, are slightly flexible when coming to a seat therein, and in so far as fitting grooves of various widths are universal in character. When brought to their extreme limit of movement the sections are automatically locked by the self-locking mechanism, which being accessible only from the inside of the vehicle provides a somewhat restraining influence on those individuals who otherwise might be tempted to commit theft of articles left within the automobile.

Furthermore it is of considerable advantage to a business man after parking his car in the street on a hot day to be able to secure a considerable amount of protection of his property and still obtain the benefit of seating himself in a thoroughly ventilated vehicle when he again wishes to use it.

The device can be installed on the automobile in a few seconds of time—and as quickly removed.

Having thus described my invention, what I claim and desire to secure by Letters Patent is:

1. An extensible window screen having two telescopically arranged sections, a wedge-shaped rail disposed on three edges of the screen when the sections are assembled, and means to prevent retraction of said section—one within the other, after being extended into any one of various positions, relatively.

2. An extensible window screen, adapted to operate within the window frame of a motor vehicle, the edges of said screen adapted to engage the window pane grooves therein, comprising two telescoping sections, one slideable within the other, each section including a frame, a screen cloth secured to said frame, a wedge-shaped rail integral with and disposed on two adjacent edges of said frame, and a concaved rail on the bottom of said frame, the two rails on the bottom of the two respective sections being in slideable engagement, relatively.

3. A window screen adapted to operate in a grooved window-frame, comprising two screen sections susceptible of extension and retraction with respect to each other, a wedge-shaped rail projecting from two adjacent edges of each of said sections—the rails on the upper, longitudinal portions of the respective sections making mutual and slideable engagement, a rail on the bottom longitudinal portion of each section of slightly arcuate form, said bottom rails being in slideable engagement, relatively, a rack on one of said sections, a pawl on the other of the said sections adapted to engage said rack, and means

normally holding said pawl against disengagement from said rack.

4. In a device of the character described, adapted for use in a window frame having relatively wide grooves in three sides thereof for the purpose of receiving a vertically slideable window pane, comprising in combination, two extensible screen sections, a rail on each of said sections, of wedge-shape form, the base of the wedge being greater in width than that of the said grooves, said rails being disposed on the vertical, outer edge and across the upper longitudinal edge of each section, said upper rails of the two sections making mutual and slideable engagement, a base rail extending from the lower portion of each section, said rails slidably engaging each other and adapted to be engaged by the said window pane, when raised, and means to secure said sections so that the vertical, wedge-shaped rails may be held in close engagement with said grooves.

5. A device of the character described, adapted to be mounted in the grooves for the window pane of a motor vehicle window, comprising in combination, two gnomonic shaped frames disposed, laterally, in slightly spaced relation, screen cloth secured to said frames, and covering the interior space therein, an extended portion projecting outwardly from two adjacent edges of the frame of each of said sections, said portion being bent into the form of a wedge-shaped rail, the rails running longitudinally of the sections being in close and slideable engagement, relatively, an extended portion projecting from the lower, longitudinal part of each of said frames, bent to form a rail adapted to be engaged by the vertically movable window pane of said motor vehicle and so formed as to enclose the top and a portion of each side of said pane, said last mentioned rails being disposed in relatively slideable engagement, a toothed rack on one of said sections, a pawl on the other of said sections adapted to engage said toothed rack and prevent retraction of one section into the other, a spring operable to normally hold said pawl in engagement with said rack, and an arm on said pawl by which to lift it out of engagement with said rack.

In testimony whereof I affix my signature.
RAYMOND L. GOOCH.
